UNITED STATES PATENT OFFICE.

STEPHEN C. MENDENHALL AND SIMON SPARKS, OF RICHMOND, INDIANA,
ASSIGNORS TO STEPHEN C. MENDENHALL.

IMPROVEMENT IN HAND-LOOMS.

Specification forming part of Letters Patent No. **59,132**, dated October 23, 1866.

To all whom it may concern:

Be it known that we, STEPHEN C. MENDENHALL and SIMON SPARKS, both of Richmond, Wayne county, Indiana, have invented a new and useful Improvement in Looms; and we hereby declare the following to be a full, clear, and exact description thereof, reference being had to the accompanying drawings, making part of this specification.

Our invention consists, mainly, of an improvement on the self-shifting treadle-cam of the kind described in the patent of S. C. Mendenhall, granted 29th August, 1865, and relates to a device for the instantaneous retraction of the cam and grooved hub, whereby a single cam of long sweep is enabled to operate on any desired number of treadles in succession, and yet to return automatically and instantly to the starting position, so as to be ready at the proper moment to resume its action at the commencement of the series of treadles.

In the customary grooved hub employed for shifting the cam in looms, the necessary obliquity of the traverse or return groove, which crosses the others, causes it, in operating three or more treadles, to take up so much of the circumference of the hub as to seriously circumscribe that portion of the revolution allotted to the movement of the cam on the treadle, and consequently the duration of opening of the shed, while for more than four treadles it is from these causes wholly impracticable, whereas in the present improvement the cam can be given its full sweep, and can be relied upon always to come promptly to time, no matter how many treadles may be employed.

In the accompanying drawings, Figure 1 is a perspective view, representing the application of our improvement to a self-acting hand-loom. Figs. 2 and 3 represent successive positions of the cam.

The words "right" and "left" in the following specification refer to the right or left of the machine in respect to the operator.

The treadle cam-shaft A is journaled horizontally a suitable distance in rear of the heddle-frame, and may be rotated by an endless chain, B, extending from the driver C to a spurred pulley or sprocket, D, on the right end of the cam-shaft. The said shaft A has a shoulder, a, and a feather, a', to permit a limited

sliding motion of the cam, and yet compel its rotation with the shaft.

The driver C revolves on a stud-shaft, N, affixed adjustably to the frame, so as to enable the tightening of the belt or chain.

The present illustration contains but four treadles, 1 2 3 4, and as many grooves in the cam-hub; but our plan enables the employment of a much larger number.

Our cam E has a short concentric depressed portion, e, which traverses without depressing the treadle during the retraction of the cam. From the portion e the cam rises rapidly at e' to reach the long portion e'', which, like the portion e, is concentric, but is as much greater in radius as the desired stroke of the treadles.

The portion e'' should occupy not less than two-thirds of the circuit of the cam, in order that the shed of the warp may be held open and clear of the woof-thread almost until the very instant of the final stroke of the batten in laying up the said thread.

The above provision is especially important in weaving many descriptions of woolen goods whose warp-threads abound in knots and other obstructions, which, when the shed is closed too soon, are liable to become entangled in the woof.

The portion e'' terminates precipitously at e''', in order to allow each treadle in succession to promptly resume its horizontal position, so as to slacken the shed at the precise juncture of time when the batten is approaching the end of its beat to lay up the woof-thread.

The cam E and its hub F, while made capable of being slid along the shaft A, are compelled to rotate in common with said shaft by means of a feather, a'.

A spring, G, acts to return the cam to its starting-point against the shoulder a and to hold it there, save when shifted by the action of the finger.

The cam-hub has a series of grooves, 1 2 3 4, which, for about seven-eighths of the circle, are in equidistant planes of revolution and communicate each with the one next in order by means of an oblique channel, 1' 2' 3'.

Hinged to the cross-rail H is a finger, I, which, when not specially disengaged, is pressed into the grooves of the hub by the action of a spring, J.

The bottom of the last groove, 4, terminates in a rise, K, which, as the rotation of the hub continues, elevates the finger clear of the periphery of the hub.

L is a stop which momentarily detains the hub to give time for the engagement of a spring catch, M, whose duty it is to hold the finger I out of the grooves while the cam and hub are shot back to the first position by means of the retracting-spring G.

Projecting from the left end of the hub is a releasing-cam, O, which at the proper moment, impinging against the spring-catch M, acts to disengage it from the finger, so as to allow the latter to drop again into the groove 1 in the hub. Butts or stops i' projecting from the finger I serve to limit its vibrations.

In order to insure an orderly and concerted action among all the parts with as little shafting or cog-gearing as possible, and yet enable the operator to stand square with and facing the front of the machine, and to afford a crank-motion on the plane parallel to the motion of the batten, and so that the crank shall be at its most effective position when the batten is in the act of striking up the woof-thread, I have provided a driving spurred pulley or sprocket, C, and have connected the same to a similar sprocket, D, on the cam-shaft by means of an endless belt, B b, having metallic eyelets.

The winch or hand-crank C' is affixed at such position to the sprocket C, and the sprockets C and D are so connected by pitman P to the batten Q, as to bring the winch C' and the pitmen P P all at or near their dead-points, and with the weight of the operator bearing upon the winch C', so as to concentrate the greatest force at this special and important juncture of the operation, enabling the operator to lay up the woof-thread firmly, and insuring a dense and heavy fabric without the necessity of fulling.

The eyeleted belt B b may be formed of canvas or leather with metallic eyes, or may be simply a metallic chain.

The essential requisites of said belt are pli-

ability without extensibility and the faculty of communicating positive motion from pulley to pulley.

We claim herein as new and of our invention—

1. The peculiarly-shaped cam E e e' e'' e''', in the described combination with the grooved hub F, constructed as described, and a series of treadles, 1 2 3 4, or more, constructed as described, whereby one cam is made to operate all the treadles, and also to keep the treadles depressed during almost the entire revolution of the cam.

2. The rise K and stop L, in the described combination with grooved cam-hub F, as and for the purpose set forth.

3. In combination with the cam E e e' e'' e''' and hub F, grooved as shown and described, the retracting-spring G.

4. The finger I, hinged to the cross-rail H and provided with a spring, J, for the purpose set forth.

5. In the described combination, the yielding and spring-sustained finger I and the spring-catch M for the momentary detention of the finger outside of the hub, as set forth.

6. The releasing-cam O, in the described combination with the spring-catch M and finger I.

7. The combination of grooved cam-hub F and the yielding and spring-sustained finger I.

8. The arrangement of feathered and shoulered shaft A a a', cam E e e' e'' e''', grooved hub F, rise K, stop L, releasing-cam O, spring-catch M, and retracting-spring G.

9. In combination with the elements of the clause immediately preceding, the spurred pulleys C and D, winch C', eyeleted belt or chain B b, pitmen P P, and batten Q.

In testimony of which invention we hereunto set our hands.

STEPHEN C. MENDENHALL.
SIMON SPARKS.
